BABY WALKER

Matilda D. Welsh, Ladue, Mo.

Application August 17, 1950, Serial No. 180,053

7 Claims. (Cl. 155—22)

1

This invention pertains to a baby walker of the type which may be folded when not in use so as to occupy reduced space for storage.

The structure comprises a base frame mounted on casters, and a seat frame supported above said base frame on collapsible legs. Each leg is formed in the shape of a toggle, the ends of which are pivoted respectively to the base frame and the seat frame so as to be foldable in order to lower the seat frame upon the base frame. A second toggle connects the hinge pivot of each leg to a point on the base frame spaced from the lower pivot of said leg. This second toggle provides a brace for the leg. Each of these toggles is arranged to be locked against pivotal movement in one direction but free to move in the opposite direction. Accordingly, when the toggles are in extended position, both are locked and a rigid structure is provided. However, the toggles may be broken and folded so as to lower the seat frame on the base frame to make a compact structure.

A preferred embodiment of this invention is shown in the accompanying drawings, in which

Fig. 1 is a plan view of a walker embodying this invention;

Fig. 2 is a righthand side view of Fig. 1;

Fig. 3 is a detail section taken on line 3—3 of Fig. 2, enlarged;

Fig. 4 is a detail section on line 4—4 of Fig. 2, enlarged;

Fig. 5 is a side view of the walker in collapsed position; and

Fig. 6 is a detail plan view of one of the leg structures in collapsed position.

Referring to the drawings, 1 designates a base frame which may be a simple rectangle of strap iron, or the like. This may be mounted on casters 2 so as to be movable about the floor and may, if desired, be provided with a rubber protective covering 1a. Supported above the base frame 1 is a seat frame 3 which may also be of strap iron of appropriate outline. This frame may be provided with a pair of side members 4 forming convenient means for attachment of the legs. A seat 5 of any suitable design, which may be of fabric, or the like, is suspended from the frame 3.

At each end of members 4, which ends form the corners of the seat frame, a supporting leg is attached. In the structure illustrated such leg comprises an upper section 6 pivoted at 7 to a member 4. The member 6 may be part of a U-shaped member, the bottom of which forms a cross member 8 extending across to the other side of the seat frame having a similar member

2

6 providing the upper section for another leg. A lower section 9 of the leg is pivoted at 10 to the base frame 1 and is connected by a pivot 11 to the section 6, said pivot 11 forms the hinge of a toggle formed between sections 6 and 9. As may be seen from Fig. 3, the section 9 is connected to the section 6 on the inside of the U of which that section forms a part. Accordingly, the member 8 of said U passes on the outside of the section 9, so that pivotal movement of that section in the direction toward the member 8 is prevented. The member 8 therefore locks the leg toggle against movement in that direction. Said toggle is, however, free to pivot in the opposite direction, that is, with the pivot 11 moving outward with respect to the seat 5.

In order to brace the leg toggle, a second toggle, is provided consisting of an upper section 12 and a lower section 13 pivoted to each other at 14. 20 This second toggle is pivoted at one end on the pivot 11 and at its lower end on a pivot 15 on the base frame 1 at a point spaced outward from the pivot 10. In this second toggle the section 12 is bent outward and then offset as shown at 25 16 so as to extend across the outside or lower section 13. This locks the second toggle against inward movement of the pivot 14 while permitting outward movement thereof. These locking devices, provided by the member 8 and the offset portion 16, are arranged to lock each toggle in a position slightly past dead-center, so that said toggles will be stable in that position. Thus a rigid structure is provided when the toggles 6 and 9 are in extended position. Furthermore, the 30 leg structure on the right and left of Fig. 2 are faced in opposite directions, so that once in extended position they are locked so as to be rigid against any side forces applied thereto by the seat frame 3.

40 When it is desired to fold the structure, it is only necessary to break the toggles by moving the pivot 14 outward, which also moves the pivot 11 outward, whereupon both toggles may be folded to lower the seat frame upon the base frame, as shown in Fig. 5. The pivot 11 may have an extension 11' which may rest on the section 13 when in folded position, as shown in Figs. 5 and 6 to prevent the toggle 12—13 from locking in this position, thereby making it difficult to unfold the device.

45 It will be seen, therefore, that this invention provides a simple structure which may be made of very light materials, and being constructed almost entirely of strap iron, or similar stock, will be cheap to manufacture. The structure is

such that it is easily extended by simply lifting the seat frame, and then forms a rigid structure in which a child may be permitted to rest without fear of an accident. When folded as described, it collapses to a relatively small space so it may be conveniently stored when not in use.

Various changes may be made in the details of construction, within the scope of the appended claims, without departing from the spirit of this invention. Parts of the invention may be used without the whole, and improvements may be added while retaining some or all of the advantages of the invention.

I claim:

1. In a baby walker of the character described, comprising, a seat frame, a base frame mounted on casters, a leg supporting said seat frame on said base frame, said leg being formed of a pair of sections joined by a pivot to form a toggle, one end of which is pivoted to said seat frame and the other end to said base frame, and a second toggle providing a brace connecting said pivot to said base frame to sustain said leg in extended position.

2. In a baby walker of the character described, comprising, a seat frame, a base frame mounted on casters, a leg supporting said seat frame on said base frame, said leg being formed of a pair of sections joined by a pivot to form a toggle, one end of which is pivoted to said seat frame and the other end to said base frame, and a second toggle providing a brace connecting said pivot to said base frame to sustain said leg in extended position, said toggles being locked against pivotal movement in one direction but free to move in the opposite direction.

3. In a baby walker of the character described, comprising, a seat frame, a base frame mounted on casters, a leg supporting said seat frame on said base frame, said leg being formed of a pair of sections joined by a pivot to form a toggle, one end of which is pivoted to one side of said seat frame and the other end to said base frame, and a member connected to one of said sections and extending crosswise of said base frame, said member providing a stop to lock said toggle against pivotal movement in one direction.

4. In a baby walker of the character described, comprising, a seat frame, a base frame mounted on casters, a leg supporting said seat frame on said base frame, said leg being formed of a pair of sections joined by a pivot to form a toggle, one end of which is pivoted to one side of said seat frame and the other end to said base frame, a

member connected to one of said sections and extending crosswise of said base frame, said member providing a stop to lock said toggle against pivotal movement in one direction, and a second toggle providing a brace connecting said pivot to said base frame to sustain said leg in extended position.

5. In a baby walker of the character described, comprising, a seat frame, a base frame mounted on casters, a U-shaped member providing a pair of leg sections pivoted to opposite sides of said seat frame and a cross member joining said sections, and a second pair of leg sections pivoted one to each of said first sections inside the U and forming with said first sections toggles which are locked by said cross member against pivotal movement in one direction.

6. In a baby walker of the character described, comprising, a seat frame, a base frame mounted on casters, a U-shaped member providing a pair of leg sections pivoted to opposite sides of said seat frame and a cross member joining said sections, a second pair of leg sections pivoted one to each of said first sections inside the U and forming with said first sections toggles which are locked by said cross member against pivotal movement in one direction, and a second toggle providing a brace connecting one of said legs to said base frame to sustain said leg in extended position.

7. A baby walker of the character described, comprising, a seat frame, a base frame mounted on casters, and a foldable supporting structure for said seat frame including, a pair of U-shaped members each providing two leg sections pivoted at their ends to the corners of said seat frame, lower leg sections pivoted respectively to said first sections and to said base frame to form toggle legs, and toggle braces connecting said legs to said base frame, said toggles being formed with inter-engaging portions whereby they are locked against pivotal movement in one direction so as to form a rigid braced structure when in extended position.
